UNITED STATES PATENT OFFICE.

SYVER LOE, OF MINNEAPOLIS, MINNESOTA, ASSIGNOR OF ONE-HALF TO
FOSSTON MANUFACTURING COMPANY, A CORPORATION OF MINNESOTA.

ALTERNATING ROTARY GEARING.

No. 839,863.

Specification of Letters Patent.

Patented Jan. 1, 1907.

Application filed February 23, 1906. Serial No. 302,417.

To all whom it may concern:

Be it known that I, SYVER LOE, a citizen of the United States, residing at Minneapolis, county of Hennepin, and State of Minnesota, have invented certain new and useful Improvements in Alternating Rotary Gearing, of which the following is a specification.

My invention relates to gearing adapted to rotate alternately in opposite directions.

10 The principal object of the invention is to provide an easy-running operating mechanism for washing-machines, churning, &c., adapted to automatically reverse the revolutions of the drum or other device while the 15 rotations of the driving-shaft continue in one direction.

My improvements are illustrated in the accompanying drawings, in which—

20 Figure 1 is an end elevation of a washing-machine equipped with my improvements. Fig. 2 is an enlarged central vertical section of a portion of the machine and gearing on the line *x* *x* of Fig. 1. Fig. 3 is an enlarged front view of the operating mechanism and adjacent parts shown in Fig. 1. Fig. 4 is a 25 top view of the same, some of the parts being shown in horizontal section; and Figs. 5 to 10 show details of parts to be hereinafter particularly described.

30 In the drawings, 1 designates the frame; 2, one of the bridge-trees; 3, the stationary cylindrical casing, and 4 the interior perforated drum of a washing-machine. The trunnions 5 of the drum are secured to its heads 6 by 35 plates 7, to which the trunnions are rigidly fastened, and the latter extend through openings in the casing and are journaled in boxes 8 on the bridge-trees outside the casing.

35 The drum is revolved by the turning of the 40 hand-wheel 9 by means of the handle 10, which serves to rotate the stub-shaft 11 and by the operation of the intermediate gears turns one of the trunnions or axles 5. This shaft 11 is mounted in journal-boxes 12, which are supported by brackets 13, attached to one of the bridge-trees 2.

On the shaft 11 adjacent to the boxes 12 are loose bevel-pinion 14 and 15, in mesh with opposite portions of a large bevel gear-wheel 16, which is fast on the trunnion 5. The hubs of the pinions 14 and 15 have inward circular flanges provided with teeth and constitute clutch members 17. The corresponding intermediate clutch members 18

are also loose and slideable on the shaft 11. Inside of each of the clutch members 17 is a 55 collar 19, fixed to the shaft 11 by a pin 20 or otherwise and having grooves 21 extending along its outer surface parallel with the shaft, and each clutch member 18 carries a 60 pair of pins 22, arranged to slide in while at all times remaining within the grooves 21. The purpose of this construction is to insure the prompt and accurate intermeshing of the teeth of the clutch members when they are 65 reciprocated to contact.

The shifting members 18 are adapted to turn with while they are slideable upon the shaft 11 and are connected to a shifter-carriage 23 by yokes 24, which loosely engage 70 in annular grooves 25 in their hubs or bosses 26, the yokes being rigidly attached to the carriage above and below the hubs. The carriage is guided in its reciprocatory movements by pins or screws 27, secured to lugs 75 28 on the base of the carriage and extending through slots in a horizontal plate 29, which is attached to shelves 30 on the brackets 13.

The carriage 23 is reciprocated by means of a shifting-lever 31. This lever is carried 80 by the threaded end portion 32 of the drum-axle 5, so that the rotations of the axle will cause the lever to move inward toward the gear-wheel 16 or outward and away from it, depending upon the direction of rotation of 85 the axle. To throw the lever, and consequently change the direction of its travel on the axle 5, an arm 33 is secured to the end of the axle, and from it a lug or pin 34 projects inward in position to be engaged by the lever 90 when the latter reaches that end of the screw. A pin or projection 35 on the gear-wheel 16 engages the lever when it reaches the inward limit of travel on the screw. While the axle 5 rotates in one direction, the lever will be 95 caused to travel outward on the axle until it is engaged by the lug 34 on the arm 33, and upon reversal of the axle rotation the lever will be caused to move inward on the axle until it is engaged by the pin 35 on the gear-wheel.

The upper arms 36 of the carriage 23, on which the yokes 24 are provided, are suitably curved in outward and upward direction to be frictionally engaged and moved by the alternate contact of antifriction-rollers 37, which are mounted on opposite sides of the hub or boss 38 of the lever 31. The arm 33 and the

lugs 34 and 35 are so arranged and positioned that upon engagement of either lug with the lever it will lift the lever and swing upward slightly past perpendicular position, whereupon the lever will gravitate to its seat at the opposite side, and thereby effect a reversal of the clutch-contacts. The lever is weighted at its upper or free end by the enlargement 39 to cause it to gravitate quickly and effectively in causing the alternations of engagement of the clutches, and its weight serves as an aid in holding the clutches in place. The lower of the two rollers 37, which seats in an annular recess 40 in the carriage 23 below the axis of the shaft 11, serves to lock the lever in place until it is again lifted by the engagement of one of the lugs 34 or 35.

In operation the crank-wheel may be turned continuously in the same direction, while the gearing automatically and periodically changes the direction of the rotation of the axis of the drum. If upon starting to turn the crank the shifting-lever is in the position shown by full lines in Fig. 3, continuance of the operation will carry the lever inward on the threaded axle 32 until it is engaged by the lug 34 on the arm 33, which will lift the lever and carry it past the perpendicular and allow it to gravitate toward the opposite side. As the lever descends toward the right the right-hand roller 37 will engage the inclined surface of the adjacent carriage-arm 36 and slide the carriage toward the right, and thereby separate the left-hand pair of clutch members and carry the right-hand pair into operative contact. This change of clutch-contact will change the effective pinion-drive from the left-hand pinion 14 to the right-hand pinion 15, and thus reverse the rotation of the gear-wheel 16, and thereby the movement of the axis 5. The movement in the direction last assumed will then continue until the lever has traveled inward on the axle far enough to bring the pin 35 on the gear 16 to contact with the lever, whereupon the latter will be lifted upward past vertical position and permitted to gravitate to the left to the assumed starting position and the operative devices will again be in their first positions.

Having described my invention, what I claim, and desire to secure by Letters Patent, is—

1. An alternating gearing mechanism, comprising gearing and a driving and a driven shaft and a pair of clutches on the former shaft, in combination with a reciprocating carriage for the loose clutch members, an oscillatory lever for engaging the carriage to reciprocate it, a screw on the driven shaft for moving the lever forth and back transversely to the carriage, and devices operating at the limits of such movements to throw the lever in opposite directions to reciprocate the carriage and reverse the direction of rotation of the driven shaft, substantially as set forth.

2. An alternating rotary gearing, comprising a driven shaft, a bevel gear-wheel thereon, a driving-shaft, a pair of loose bevel-pinions thereon meshing with the gear-wheel at opposite points, clutch members carried by the pinions, corresponding loose clutch members, an intermediate reciprocating carriage for the latter, an oscillatory lever fulcrumed on a threaded portion of the driven shaft for periodically reciprocating the carriage, and devices operating at the limits of the forth and back movements of the lever to throw it in opposite directions to move the carriage and alternate the clutch-contacts, substantially as set forth.

3. An alternating rotary gearing, comprising a driven shaft, a bevel gear-wheel thereon, a driving-shaft, a pair of loose bevel-pinions thereon meshing with the gear-wheel at opposite points, clutch members carried by the pinions, corresponding loose clutch members, an intermediate reciprocating carriage for the latter, an oscillatory lever fulcrumed on a threaded portion of the driven shaft, and projections on the gear-wheel and driven shaft for engaging the lever at the limits of its travel on the shaft to throw it alternately in opposite directions to alternate the clutch-contacts, substantially as set forth,

4. An alternating rotary gearing, comprising a driven shaft, a bevel gear-wheel thereon, a driving-shaft, a pair of loose bevel-pinions thereon meshing with the gear-wheel at opposite points, clutch members carried by the pinions, corresponding loose clutch members provided with horizontal pins, a collar fixed on the shaft and having grooves in which said pins slide, an intermediate reciprocating carriage for the loose clutch members, and an automatically-operating shifter for periodically reciprocating the carriage to alternate the engagement of the clutches and reverse the direction of revolution of the gear-wheel, substantially as set forth.

5. An alternating rotary gearing, comprising a driven shaft, a bevel gear-wheel thereon, a driving-shaft, a pair of loose bevel-pinions thereon meshing with the gear-wheel at opposite points, clutch members carried by the pinions, corresponding loose clutch members provided with horizontal pins, a collar fixed on the shaft and having grooves in which said pins slide, an intermediate reciprocating carriage for the loose clutch members, an oscillatory lever fulcrumed on a threaded portion of the driven shaft, and projections on the gear-wheel and driven shaft for engaging the lever at the limits of its travel on the shaft to throw it alternately in opposite directions to alternate the clutch-contacts, substantially as set forth.

6. In combination, a pair of clutches, an intermediate reciprocating clutch-carriage having opposite upwardly-inclined surfaces, an oscillatory shifter-lever fulcrumed interme-

diate said inclines and having rollers arranged to alternately engage them to reciprocate the carriage, and means for automatically oscillating the lever at intervals, substantially as set forth.

7. In combination, a pair of clutches, an intermediate reciprocating clutch-carriage having opposite upwardly-inclined surfaces, a weighted shifter-lever fulcrumed intermediate said inclines and having rollers arranged to alternately engage them to reciprocate the carriage, and means for automatically oscillating the lever past the perpendicular at intervals, substantially as set forth.

8. An alternating rotary gearing, comprising a driven shaft, a bevel gear-wheel thereon, a driving-shaft, a pair of loose bevel-pinions thereon meshing with the gear-wheel at opposite points, clutch members carried by the pinions, corresponding loose clutch members, an intermediate reciprocating carriage for the latter, a shifter for periodically reciprocating the carriage to alternate the engagement of the clutches, means provided

on the gear-wheel for throwing the shifter in one direction, and means provided on the driven shaft for throwing it in the opposite direction, substantially as set forth.

9. In combination, a pair of clutches, an intermediate reciprocating clutch-carriage having opposite upwardly-inclined surfaces, an oscillatory shifter-lever fulcrumed intermediate said inclines and having rollers arranged at opposite sides near its fulcrum for alternately engaging said surfaces to reciprocate the carriage and for locking the carriage in place at the extremes of its movements, and means for automatically oscillating the lever at intervals, substantially as set forth.

In testimony whereof I have signed my name to this specification, in the presence of two subscribing witnesses, this 10th day of February, 1906.

SYVER LOE.
